S. MARCUS.

ARTIFICIAL EYES FOR DOLLS, DISPLAY FIGURES, AND THE LIKE.

APPLICATION FILED OCT. 29, 1919.

1,331,272.

Patented Feb. 17, 1920.

UNITED STATES PATENT OFFICE.

SAMUEL MARCUS, OF BROOKLYN, NEW YORK, ASSIGNOR TO F. & M. NOVELTY CO., INC.,
OF NEW YORK, N. Y., A CORPORATION OF NEW YORK.

ARTIFICIAL EYES FOR DOLLS, DISPLAY-FIGURES, AND THE LIKE.

1,331,272.

Specification of Letters Patent.

Patented Feb. 17, 1920.

Application filed October 29, 1919. Serial No. 334,175.

To all whom it may concern:

Be it known that I, SAMUEL MARCUS, a citizen of the United States, and a resident of Brooklyn, in the county of Kings and State of New York, have invented certain new and useful Improvements in Artificial Eyes for Dolls, Display-Figures, and the like, of which the following is a specification.

10 The invention relates to improvements in the manufacture of eyes for dolls and other purposes, such as display figures, and the invention consists in the novel features hereinafter described, and particularly pointed out in the claims.

The invention pertains more especially to novel shells of metal for receiving the bridge piece connecting the eyes of a pair or set and the covering material, such as thin sheet celluloid, upon which may be printed a representation of the iris of the eye. The invention also pertains to a novel construction of hanger for suspending the bridge piece and also suspending the weight which 25 effects the movements of the eyes to open and closed position in accordance with the position of the doll.

One of the objects of the invention is to produce an eye structure which is capable 30 of being angularly adjusted to suit the sockets of the eyes in the heads of dolls, these sockets being somewhat irregular in different doll heads, and another purpose of the invention is to provide a novel application of 35 a spring to the hanger adapted to press the eyes with reasonable firmness against the sockets therefor in the head of a doll.

The invention will be fully understood 40 from the detailed description hereinafter presented, reference being had to the accompanying drawings, in which:

Figure 1 is a vertical section through the face of a doll and eye mechanism embodying the essential features of my invention, the 45 section through the eye mechanism being taken on the dotted line 1—1 of Fig. 2;

Fig. 2 is a rear elevation of an eye-set embodying my invention, the same being shown on a larger scale than of Fig. 1 and as 50 detached from the inner surface of the doll's face;

Fig. 3 is an enlarged vertical section through a portion of the same, taken on the dotted line 3—3 of Fig. 2;

Fig. 4 is an inner face view of a portion 55 of the same, a part of the bridge piece being broken away and the celluloid covering for the eye-shell being in section on the dotted line 4—4 of Fig. 5.

Fig. 5 is a sectional view through the 60 same, taken on the dotted line 5—5 of Fig. 4;

Fig. 6 illustrates a modified form of the invention, Fig. 6 being a vertical sectional view through one of the eyes and illustrating a pair of eccentrics as the means for 65 securing the eye to the bridge piece;

Fig. 7 is a corresponding view of the same illustrating the eccentrics in their released position or prior to having been tightened upon the bridge piece by being turned to the 70 position in which they are shown in Fig. 6;

Fig. 8 is a sectional view through the same, taken on the dotted line 8—8 of Fig. 6, and

Fig. 9 is a sectional view through the 75 same, taken on the dotted line 9—9 of Fig. 6.

In the drawings, 10 indicates the face portion of the head of an ordinary doll and 11, 12, respectively, indicate the right eye and left eye for the doll. The eyes 11, 12 80 are of substantially corresponding construction, and each eye has an inner substantially hemi-spherical metal shell 13 and an outer covering shell 14 which may be of celluloid and bear a representation of the iris of an 85 eye. The metal shells 13 are of special construction and involve important features of my invention, which features will presently be explained. The eyes 11, 12 are adjustably supported upon a bridge piece 15, 90 which may be a plain stiff rod of wire, and this bridge piece is pivotally mounted in slotted ears 16 bent forwardly from a metal plate or hanger 17, which is intended to be secured against the inner face of the doll 95 117, as shown in Fig. 1. The slots in the ears 16 are numbered 18 and correspond with the slots forming a part of my invention described and claimed in my application 100 for Letters Patent filed December 31, 1918, Serial No. 269,082. The hanger 17 is formed at its upper end with an opening 19 into which a portion of the cementitious material 117 enters and which cooperates 105 with said material in the firm securing of the eye-set to the inner face of the head of the doll. The plate hanger 17 has secured

to it a bent spring 20 whose lower ends press against the bridge-piece 15 at opposite sides of the center thereof, said spring 20 being substantially in the outline of an ordinary hair-pin, its bent portion being extended upwardly and its two leg members downwardly and engaging the bridge-piece 15, as shown in Fig. 1. In this instance I secure the spring 20 to the plate or hanger 17 by cutting two transverse slits 21 in said plate or hanger and passing the bent end of the spring through said slits, the metal strip 22 formed by the slitting of the plate 17 being then crowded against the adjacent surfaces of the spring 20 so as to bind said spring in position. The spring 20 may thus be secured in position on the plate or hanger 17 without the use of solder or other foreign fastening means. The spring 20 may further be fastened to the hanger by having its upper bent end bent rearwardly through the opening 19 thereof and turned downwardly against the inner or rear face of the hanger, thus constituting a hook which would prevent any possible downward withdrawal of the spring from the hanger or plate 17. One feature of my invention resides in the method proposed for securing the spring 20 to the hanger or plate 17, and the other features of my invention reside in the novel shells 13 for the individual eyes, this second feature having to do more particularly with the novel means for securing the eyes to the end portions of the bridge-piece 15.

At the center of the bridge-piece 15 I secure the upper end of the usual rod 23 carrying at its lower end the weight 24 of customary construction and performing the usual known function of effecting the turning of the eyes in accordance with the position of the doll.

Referring to the metal shells 13 shown in Figs. 1 to 5 inclusive, I would say that these shells are each in one integral piece of sheet metal formed from a sheet metal blank and slit and stamped up to create the outer hemispherical portion or body of the shell 25, a transverse strip 26 extending from one edge to the other of the body portion 25, and ears 27 which project forwardly from the strip 26 and from opposite edges thereof, as shown in Fig. 5, said ears 27 becoming thus spaced apart, and by preference concealed within the body portion 25. The strip or cross-bar 26 has a threaded hole 28 in it to receive the adjusting screw 29 by which the eye may be fastened to the bridge 15. The ears 27 are formed with alined apertures 30 through which the end of the bridge-piece 15 may be passed and thereafter the eye may be secured to said bridge-piece by turning the screw 29 inwardly against the bridge-piece to bind the same against the ears 27. At its opposite edges in line with

the bridge 15 each shell 13 is cut away, as at 31, to form spacious openings for the bridge-piece 15 and to permit the eye to be adjusted along said bridge, as occasion may require. The openings 31 also permit of the angular adjustment of the eyes to suit the sockets in the head of a doll. Should an eye when placed on the bridge and located opposite an eye socket not correctly fit the socket owing to an irregularity therein, the eye may be bent in one direction or the other to compel the eye to properly fit the socket with the iris of the eye in its correct position with respect to said socket, and this bending of the eye may be done while the eye is fastened to the bridge 15, the bending taking place in the ears 27 or strip 26 or in both said ears and strip. It may be understood on reference to Fig. 5 that if the eye there shown should not aline with the socket, although in true position on the bridge 15, said eye may be forcibly bent to the right or to the left to meet the conditions of the eye-socket, this bending being accomplished by taking hold of the eye and turning it to one direction or the other, while at the same time bending the ears 27 or strip 26 or both said ears and strip owing to the non-bendability of the bridge-piece 15, the weaker part bending when the eye is turned to the right or to the left, and that part being the ears 27 or strip 26 or both said ears and strip, since both are connected together. The part which will bend when the eye is turned, as just described, will more likely be the strip 26 which will then be given a twisting action, due to the bracing of the ears 27 by the bridge-piece 15.

Having regard to Figs. 4 and 5 more particularly, it will be seen that the blank from which the shell 13 is formed has its rear portions between the cross-strip 26 and the recesses 31 bent inwardly, as at 32, and then downwardly and inwardly as at 33, whereby the edges of the shell become strengthened and a cup portion is created with the similar formation indicated at 34, given to the end portions of the transverse strip 26. The outer or forward surface of the shell 13 is hemi-spherical in outline, and the inner or rear portion of said shell is of cup-formation and has the transverse strip 26, ears 27 and the sections 32, 33, 34.

The celluloid or other material 14 used for covering the shell 13 is carried over the rear portion of said shell, as indicated at 36 in Fig. 3, and thereby a portion of the rear surface of the shell 13 is covered over and the cup-portion at the rear face of the shell affords space to receive the edges of the celluloid shell 14, said space housing said edges of said shell 14 and serving as additional means for securing said shell 14 in rigid position. In the present instance the adjustment of the eyes to the sockets is not

performed by shifting the shells 14 on the shells 13, as has been done in some instances heretofore, but is accomplished by the bending of the eye-shell on the bridge 15, the 5 part bent being more particularly the strip 26, which extends from edge to edge of the shell 13, as shown in Fig. 4. The strip 26 is inwardly depressed in line with the depressed surfaces 33 of the shell, and this in 10 some instances makes it necessary to bulge outwardly the central portion of the strip 26, as shown in Figs. 3, 4 and 5, to bring the openings in the ears 27 into proper position to receive the bridge 15, and also to properly 15 locate the aperture 28 in said strip to receive the screw 29.

The method of employing the structure shown in Figs. 1 to 5 inclusive, will be understood from the foregoing description 20 without special further explanation. After the eyes are formed they are slipped upon the ends of the bridge-piece 15 and spaced apart to suit the spacings of the eye-sockets in the head of the doll and thereupon the 25 screws 29 are tightened to fasten the eyes upon said bridge-piece. The eyes may be turned angularly on the axis of the bridge-piece before the screws 29 are tightened or thereafter on the loosening of said screws 30 for an adjustment of the eyes to the eye sockets. A further adjustment of the eyes to the eye-sockets, which seems to be necessary very frequently, is the twisting or turning of the eyes at an angle to the axis of the 35 bridge 15, and in accordance with my invention this adjustment of the eyes to the sockets may be accomplished by forcibly turning the eyes to one side or the other, as occasion may require, and while doing so bending or 40 twisting the strip 26. The eye-set may be secured in the head of the doll by cementitious material 117 applied against the upper end of the hanger or plate 17 to anchor the same to the inner surface of the face of the 45 doll.

In the modification of my invention illustrated in Figs. 6 to 9 inclusive I depress the cross-strip 36, corresponding with the cross-strip 26 of Fig. 4, and bend the ears 37, 50 which are at opposite edges thereof, outwardly, as shown in Figs. 6 and 8, instead of inwardly or to the position in which the ears 27 are shown in Fig. 5. The ears 37 are apertured, as at 38, (Fig. 9), to receive the bridge-piece numbered 40 in this modification, and are also apertured to receive a rivet or pin 41 which is utilized to hold between the ears 37 two eccentrics or cams 42, 43 having handles 44, and adapted on the 55 bringing together of said handles to bind against the bridge-piece 40, as shown in Fig. 6, and thereby lock the eye in position thereon. Should it be desired to remove an eye from or adjust the same on the bridge 40, 60 the handles 44 of the eccentrics will be

turned outwardly in a direction from each other or to the position illustrated in Fig. 7, thereby releasing the eccentrics or cams 42, 43 from the bridge 40 and leaving the eye to be slid along said bridge. The shells numbered 45, in Figs. 6 to 9 inclusive, will be covered with celluloid shells 46 corresponding exactly with the celluloid shell 14 of Fig. 3, and the shell 45 of Fig. 6 corresponds with the other metal shells shown in the drawings with the exception, of having its cross-piece 36 depressed inwardly and its ears 37 projected outwardly or rearwardly in lieu of said cross-piece having its ears projected forwardly or into the shells in the manner indicated in Fig. 5. The constructions being so similar in many respects, I deem it unnecessary to add elaborate description as to the modification shown in Figs. 6 to 9 inclusive. The eyes shown in Figs. 6 to 9 inclusive may be conveniently adjusted along the bridge-piece in accordance with the spacing of the eye-sockets and may also be turned angularly on the bridge-piece to suit said sockets, and said eyes may also be twisted to the right or left, in the manner I have hereinbefore explained, with respect to the construction shown in Fig. 5, the cross-piece or strip 36 of Fig. 6 twisting or yielding to the movement to the right or left that may be given to the eye in adjusting the same to the eye-socket.

What I claim as my invention and desire to secure by Letters-Patent, is:

1. An eye for dolls and the like comprising a substantially hemispherical metal shell having a strip extending from edge to edge of its rear side and ears projecting angularly from opposite edges of said strip and affording bearings for the end of a bridge-piece of a pair of eyes, means for securing said shell on such bridge-piece, and an outer covering on said shell. 100

2. An eye for dolls and the like comprising a substantially hemispherical metal shell having a strip extending from edge to edge of its rear side, ears projecting angularly from opposite edges of said strip and affording bearings for the end of a bridge-piece of a pair of eyes and segmental sections integral with and extending inwardly from the edges of said shell at opposite sides of the ends of said strip and partly closing the rear side of said shell, means for securing said shell on such bridge-piece and 115 an outer covering on said shell. 120

3. An eye for dolls and the like comprising a substantially hemispherical metal shell having a strip extending from edge to edge of its rear side and ears projecting angularly from opposite edges of said strip and affording bearings for the end of a bridge-piece of a pair of eyes, means for securing said shell on such bridge-piece, and an outer covering on said shell, the end portions of 130

- said strip being inwardly depressed, and said outer covering being a shell having its edges overlapping the edges of said metal shell.
5. An eye for dolls and the like comprising a substantially hemispherical metal shell having a strip extending from edge to edge of its rear side, ears projecting angularly from opposite edges of said strip and affording bearings for the end of a bridge-piece of a pair of eyes and segmental sections integral with and extending inwardly from the edges of said shell at opposite sides of the ends of said strip and partly closing the rear side of said shell, means for securing said shell on such bridge-piece, and an outer covering on said shell, the end portions of said strip and said segmental sections being set inwardly, and said outer covering being a shell having its edges overlapping the edges of said metal shell.
6. An eye for dolls and the like comprising a substantially hemispherical metal shell having a strip extending from edge to edge of its rear side and integral at both ends therewith and capable of being twisted to adjust the eye to the eye-socket of a doll, means for securing the end of a bridge-piece of a pair of eyes to said strip, and an outer covering on said shell.
7. An eye for dolls and the like comprising a substantially hemispherical metal shell having a strip extending from edge to edge of its rear side and integral at both ends therewith and capable of being twisted to adjust the eye to the eye-socket of a doll and having ears projecting angularly therefrom and apertured to receive the end of a bridge-piece for a pair of eyes, means for securing said shell on such bridge-piece, and an outer covering on said shell.
8. In combination, a pair of eyes for a doll and the like, a bridge-piece connecting said eyes, a plate adapted to be secured to the inner surface of the head of a doll and supporting said eyes and a weight for actuating said eyes on the movement of the doll, said eyes each comprising a substantially hemispherical metal shell having a strip extending from edge to edge of its rear side and ears projected inwardly from the side edges of said strip and apertured to receive an end of said bridge-piece, means for adjustably securing said bridge-piece in the apertures of said ears, and an outer covering for said shell, said strip being capable of being twisted to adapt the eye to the eye-socket of the head of the doll.
9. In combination, a pair of eyes for a doll and the like, a bridge piece connecting said eyes, a plate adapted to be secured to the inner surface of the head of a doll and supporting said eyes, a weight for actuating said eyes on the movement of the doll, and a spring secured to said plate and acting to press said eyes against the eye-sockets of the doll, said plate having an opening at which the upper end of said spring, which is below the upper end of said plate, is exposed and at which a cementitious material may be applied for securing the plate in position.
10. In combination, a pair of eyes for a doll and the like, a bridge piece connecting said eyes, a plate adapted to be secured to the inner surface of the head of a doll and supporting said eyes, a weight for actuating said eyes on the movement of the doll, and a spring secured to said plate and acting to press said eyes against the eye-sockets of the doll, said plate having a transverse strip slit therein and a portion of said spring being inserted beneath said strip and bound to said plate therat.
11. An eye for dolls and the like comprising a substantially hemispherical metal shell having a strip extending from edge to edge of its rear side and ears projecting angularly from opposite edges of said strip and affording bearings for the end of a bridge-piece of a pair of eyes, means for securing said shell on such bridge-piece, and an outer covering on said shell, the end portions of said strip being set inwardly and its central portion bulged outwardly, and the means for securing the eye on said bridge-piece being a set screw extending forwardly through the outwardly bulged portion of said strip and engaging said bridge-piece.
12. In combination, a pair of eyes for a doll and the like, a bridge-piece connecting said eyes, a plate adapted to be secured to the inner surface of the head of a doll and supporting said eyes and a weight for actuating said eyes on the movement of the doll, said eyes each comprising a substantially hemispherical metal shell having a strip extending from edge to edge of its rear side and ears projected inwardly from the side edges of said strip and apertured to receive an end of said bridge-piece, means for adjustably securing said bridge-piece in the apertures of said ears, and an outer covering for said shell, said strip being capable of being twisted to adapt the eye to the eye-socket of the head of the doll.

socket of a doll, said bridge-piece being a stiff rod of wire and said shell and its covering at the inner side edge thereof being recessed to receive the bridge-piece and permit the angular adjustment of the eye with relation thereto.

Signed at New York city in the county of

New York and State of New York, this 27th day of October, A. D. 1919.
